UNITED STATES PATENT OFFICE.

MELVILLE P. HAYWARD, OF QUINCY, MASSACHUSETTS.

APPLE-CORER.

1,213,361.

Specification of Letters Patent. Patented Jan. 23, 1917.

Application filed February 13, 1915. Serial No. 7,938.

To all whom it may concern:

Be it known that I, MELVILLE P. HAYWARD, a citizen of the United States, residing at Quincy, in the county of Norfolk and State of Massachusetts, have invented certain new and useful Improvements in Apple-Corers; and I do hereby declare the following to be a full, clear, and exact description of the invention, such as will enable others skilled in the art to which it appertains to make and use the same.

The present invention relates to improvements in apple corers.

A serious detriment to the longer life of service of the type of apple corer to which this invention relates resides in the weakness of the point of the corer, which is first thrust into the apple in the apple-coring operation.

The object of the present invention, then, is to produce an apple corer with a reinforced point.

In the accompanying drawings illustrating the preferred form of the invention, Figure 1 is a front elevation of the improved apple corer; Fig. 2 is a rear elevation of the same; Fig. 3 is a side elevation, partly in section; Fig. 4 is an end elevation of the cutting end of the corer; and Fig. 5 is a sectional view on line 5—5 of Fig. 1.

The improved apple corer, which may be made of any suitable metal, such as tin, comprises a tapering cylindrical body 6, provided with a handle 7 rigidly secured to its larger end. Cutting edges 8 are formed on the smaller end of the cylindrical body by removing the material therefrom on an oblique or slanting line running from the end 9 back as far as the point 10. As may be observed from Fig. 3, the cutting edges

are formed on a long taper. In order that the cutting edges may cut freely, they flare outwardly slightly, as indicated in Figs. 1 and 2. A core discharge recess 11 is interposed in the body of the corer for discharging the removed cores, and is provided with a shelving wall 12 on its rear end in order to facilitate the discharge of the core, and also to prevent the core from slipping down into the larger end of the cylinder. 45 This construction also conduces to the ready cleaning of the corer. A reinforcing rib 13 is formed on the point or thrusting end of the corer, by making a depression longitudinal of the corer body in the bottom of 55 the concaved surface between the two cutting edges 8. It is obvious that this depression may extend from the inside outwardly, or from the outer side inwardly. Providing the point of the corer with this reinforcing rib prevents the point from crumpling up under the stress of continued use in being thrust into apples, or in case the corer should fall and land upon its point. The result is that the operation of coring 65 apples may be performed more expeditiously and efficiently, and the corer assured of a longer life of service.

Having thus described my invention what I claim is:

An apple corer comprising a cylindrical body terminating in a slanting cutting end having a cutting edge, and being provided with a reinforcing rib located at the extremity and forming a part of the cutting edge. 75

MELVILLE P. HAYWARD.
